(57) **CLAIM**

We claim the ornamental design of a wireless sound transmitter, as shown and described below.

DESCRIPTION

FIG. 1 is a perspective view of a wireless sound transmitter showing my new design;

FIG. 2 is a front elevational view of the wireless sound transmitter;

FIG. 3 is a rear elevational view of the wireless sound transmitter;

FIG. 4 is a left side elevational view of the wireless sound transmitter;

FIG. 5 is a right side elevational view of the wireless sound transmitter;

FIG. 6 is a plan view of the wireless sound transmitter;

FIG. 7 is a bottom view of the wireless sound transmitter; and,

FIG. 8 is a reference view of the wireless sound transmitter.
